ATTORNEY.

UNITED STATES PATENT OFFICE.

JOHN PETERSEN, OF MADISON, WISCONSIN.

AUTOMATIC HEADLIGHT REFLECTOR.

Application filed March 24, 1923. Serial No. 627,502.

To all whom it may concern:

Be it known that I, JOHN PETERSEN, a citizen of the United States, residing at Madison, in the county of Dane and State 5 of Wisconsin, have invented certain new and useful Improvements in Automatic Head-light Reflectors, of which the following is a specification.

My invention relates to automatically adjusting head-lights; and the objects of my invention are, first, to use only the top, sides, and back of a reflector with a light bulb located at the back and adjacent the lower edge of same; second, to truncate 10 the top of the reflector and place a visor across the top; third, to hinge the reflector to the top of the inside of a casing; fourth, to provide a control means attached to the inside of the side walls for keeping the 15 same in a horizontal position regardless of the grade of the road; and fifth, to so construct the casing in which the reflector is mounted that it can be applied to any head-light body as now used on road vehicles. 20

I attain these objects by the mechanism shown in the accompanying drawing in which—

Fig. 1, is a horizontal section on line 30 A—B, Fig. 2;

Fig. 2, is a partial vertical section on line C—D, Fig. 3;

Fig. 3, is a front elevation;

Fig. 4, is a front elevation of control, detached;

Fig. 5, is a side elevation of the same.

Similar numerals refer to similar parts throughout the several views.

The front of the reflector 1 is curvilinear with the top truncated, and the base at the back is semi circular with tangent sides diverging towards the front. A light bulb 2, is located within the reflector at the back and near the bottom in a socket 3, and attached or removed in the usual manner. A bracket 4, is secured to the back near the top of the reflector and is hingedly connected to a tube 5, which is rigidly secured to a casing 6, which incloses and is the frame 45 of my entire device. A beam 7, with depending plates 8, which are bi-furcated at the lower ends, is secured to the reflector on the inside and adjacent the lower and

front edges by upturned ends 9. A stand 10, comprises two vertically parallel walls 11, upon the upper and inner edges of which curved sections of gear rack 12, are secured, the curvature of the racks being concentric with the tube 5, from which the reflector is suspended. Journal boxes 13 are provided 55 grooved on opposite sides to be disposed and slide vertically in the bifurcated lower ends of the plates 8, and a shaft 14, is revolvably mounted in the said boxes, upon said shaft abutting the boxes collars 15, and 60 next spur gears 16, are mounted and between the gears at the center of the shaft, a hollow rim balance wheel 17, is secured, and within the rim a plurality of steel balls 18, are placed; a latch 19, is attached 65 to the rear end of one of the walls 11, to limit the movement backward of the balance wheel and the forward movement is adjusted by the arms 20, of the yoke 21, which is pivotally attached to the front 70 side of the walls 11, and its position adjusted by a screw 22, threaded in the stand 75 10, and a tension spring 23, leading from the outer end of the yoke to the casing 6. The reflector being suspended from the 80 top of the casing 6, by the bracket 4, would if the center of gravity was directly under the tube 5, maintain a horizontal position, but swinging free would be effected by every little pitch of the car, for that reason I 85 have decided to use the balance wheel control as shown. A change in the grade of the road will cause the weighted balance wheel to roll to a point under the tube 5, and hold it there by means of the teeth of 90 the gears 16, meshing with the rack 12, and prevent any swinging of the reflector but will quickly and automatically adjust the head-light to a position whereby the light will be on the road and kept below the eyes 95 of drivers of approaching cars. By the forward adjusting means, screw 22, lights can be adjusted to strike the road at any desired distance ahead of the car. To provide for fitting the casing 6, to different 100 head-light bodies, the outer flange is made for the largest in use and cut down for other sizes.

Having thus described my invention, I claim—

In automatically adjusting head-lights, a

truncated reflector suspended from a hinge in the top of a casing, and controlled by a bar across the bottom of same, said bar loosely connected to the shaft of a hollow 5 rim balance wheel which carries movable weights within the rim, said shaft through rollers and gears moving upon a track concentric with the hinge aforesaid.

In testimony whereof I affix my signature in the presence of two subscribing wit- 10 nesses.

JOHN PETERSEN.
